UNITED STATES PATENT OFFICE.

MICHAEL V. TRUHAN, OF BRIDGER, MONTANA.

RAILWAY CATTLE-GUARD.

1,249,556.

Specification of Letters Patent. Patented Dec. 11, 1917.

Application filed January 21, 1916. Serial No. 73,384.

To all whom it may concern:

Be it known that I, MICHAEL V. TRUHAN, a citizen of the United States, residing at Bridger, in the county of Carbon and State 5 of Montana, have invented certain new and useful Improvements in Railway Cattle-Guards, of which the following is a specification.

My invention relates to cattle guards for 10 railways and has particular reference to a new and improved device arranged adjacent the grade crossing or other non-fenced portion of a railway track for preventing the trespassing thereupon of animals.

15 The primary object of my invention is to provide a cattle guard of the class described which is simple in construction, strong and durable, effective in operation, and cheap to manufacture and install.

20 With the above and other objects in view my invention resides preferably in the construction, combination and arrangement of parts as hereinafter set forth in the specification and illustrated in the accompanying 25 drawings, in which,

Figure 1 is a top plan view of a railway cattle guard including the preferred embodiment of my invention.

Fig. 2 is a transverse sectional view taken 30 on the line 2—2 of Fig. 1.

Fig. 3 is a fragmentary longitudinal sectional view taken on the line 3—3 of Fig. 1 looking in the direction of the arrow.

Fig. 4 is an enlarged fragmentary elevational view of one of the elements forming 35 the barrier.

Similar reference characters designate corresponding parts throughout the various views of the drawings.

40 In the drawings, wherein the preferred embodiment of my invention is illustrated, I have shown a railway track comprising the running rails 10 mounted as usual on the cross ties 11. My invention comprises three 45 sections or structures, which may be identical in size and form, one of said sections being arranged between the running rails, and the other sections being arranged outside of the running rails. In view of the fact that 50 these sections may be identical I shall describe but one of the same, however, the three sections are designated in their entirety as A, B and C.

The barrier or guard comprises preferably 55 a pair or more of stringers 12 and 13 arranged in spaced parallel relation on the ties

11. The extremities of the stringers 12 and 13 are arranged in spaced parallel relation on the ties 11. The extremities of the stringers 12 and 13 are bolted or otherwise secured as 60 at 14 to the ties 11, as shown to advantage in Figs. 1 and 3. The stringers 12 and 13 form a frame for supporting the barrier members which are constructed for oscillation or rotation in the frame to provide an insecure 65 footing for an animal which will tend to frighten or prevent the animal from going upon the track either way from the grade crossing. As shown to advantage in Figs. 2 and 3 the leading guard or barrier comprises preferably a square elongated beam 16 having stub shafts 17 extending from the opposite ends thereof and mounted in suitable bearing openings formed in the stringers 12 and 13. A plurality of prongs 18 70 and 19 extend rearwardly and upwardly from said beam 16 and serve the purpose hereinafter set forth. A platform 20 is carried by one side of the beam 16 and extends forwardly of the barrier in the direction of 75 the grade crossing (not shown) so that when an animal steps upon the same the platform will be tilted, as shown in dotted lines in Fig. 3, presenting an insecure footing for the animal. In order to return the platform 80 20 to normal position I provide a pair of arms 22 having loops 23 on their free extremities connected with coil springs 24 fastened to one of the ties 11. It will thus be seen that the platform 20 is depressed 85 against the action of the springs 24. In the guarding devices B and C only one of said springs is provided in view of the fact that said guarding device would be in most instances narrower than the centrally located 90 barrier A. In order to limit the downward movement of the platform 20 and thereby prevent catching the animal's hoof, a stop 95 25 is provided on one of the stringers.

Should the animal succeed in passing the 100 depressible platform 20 a plurality of rotatable bars 26 are mounted on the stringers 12 and 13, said bars having stub shafts 27 similar to the stub shafts 17 of the beam 16 hereinbefore described. A plurality of 105 radiating prongs 28 are carried by the various faces of the bar 26 and not only serve to provide an insecure footing for the animal, but will impinge upon the animal's foot causing the animal to necessarily withdraw. 110

As shown to advantage in Fig. 4 the spikes or prongs 18, 19 and 28 are preferably pro-

vided with threaded shanks 29 to permit the renewal of the prongs in case of damage to the same. It will be noted that the prongs shown in Fig. 4 are of a slightly different shape from those shown in the remaining figures of the drawings, but this does not necessarily enter into the invention, any desired shape of prong being applicable. It will be readily apparent that more than one of the depressible platforms 20 may be employed on a single frame in conjunction with the other guarding devices.

From the above description taken in connection with the accompanying drawings it is thought that a clear and comprehensive understanding of the construction, operation and advantages of my invention may be readily gathered, and while I have shown and described the same as embodying a specific structure I desire that it be understood that I may make such changes therein which do not depart from the spirit and scope of the invention as claimed.

25 I claim:

1. In a cattle guard, the combination with the frame, of a plurality of rotatable spiked bars on the frame, a depressible platform on one of the bars at the entrance to the frame,

and a resilient member for supporting the platform in a normal position.

2. In a cattle guard, the combination with the frame, of a plurality of rotatable spiked bars mounted on the frame, a depressible platform secured to one of the bars at the longitudinal entrance to the frame, stops at either side of the platform bar, and a resilient member for holding the platform in engagement with one of the stops, the other stop being adapted to limit the downward movement of the depressible platform when depressed by a weight.

3. In a railway cattle guard, the combination with the frame arranged parallel with the rails, of a plurality of spiked bars rotatably supported on the frame, a spring pressed platform mounted on one of the bars at the head and entrance end to the frame, and stops arranged at the side of the platform supporting bar for limiting the rotatable movement of the platform bar.

In testimony whereof I affix my signature in presence of two witnesses.

MICHAEL V. TRUHAN.
